COMPONENT CHECKING CIRCUIT FOR
BURNER CONTROL APPARATUSJohn M. Wilson, Minneapolis, Minn., assignor
to Minneapolis-Honeywell Regulator Company,
Minneapolis, Minn., a corporation of Delaware

Application August 9, 1948, Serial No. 43,254

8 Claims. (Cl. 158—28)

1

The present invention relates to the control of a fuel burner. More particularly, the present invention is concerned with a burner control which will maintain the burner inoperative in the event of flame failure or upon a false indication of flame.

In present day burner controls, it has been found desirable to provide safety devices which will render the controlled burner inoperative in the event that combustion fails to take place when the burner is started up or in the event that combustion fails after having been initiated. In addition to this, it has been found necessary to provide for rendering the burner inoperative in the event that the device for indicating proper operation of the burner falsely indicates burner operation when there is no need for such operation. In my copending application for "Fuel Burner Safety Control System," Serial No. 731,998, filed March 3, 1947, I have disclosed an arrangement where a fuel burner is rendered inoperative in the event there is a flame failure or in the event that there is a false indication of flame by the flame detecting device. In either event, the burner control will maintain the burner inoperative until such time as the fault has been removed from the control.

The present invention is concerned with a burner control of the type disclosed in my copending application. The present invention provides a burner control requiring a minimum of switch contacts for accomplishing the desired control functions and still maintains a high degree of safety. This is accomplished by providing a combustion or flame detector which has overlapping in and out contacts for connecting the safety cutout device into and out of an energizing circuit in accordance with the presence or absence of a condition which might require rendering the burner inoperative.

It is therefore an object of the present invention to provide an improved burner control apparatus which requires a minimum of switch contacts and which is effective to maintain the burner inoperative in the event combustion fails or there is a false indication of flame.

Another object of the present invention is to provide an improved burner control which utilizes overlapping switch contacts to provide an apparatus having a minimum of switch contacts and which is effective to maintain the burner inoperative in the event of combustion failure or false indication of flame by the control apparatus.

Still another object of the present invention is to provide an improved burner control apparatus which has a flame detection apparatus with over-

2

lapping in and out contacts and which apparatus is effective to connect or disconnect a burner safety cutout device from a source of power whenever there is a condition of operation of the burner, or the control, which requires such connection or disconnection.

These and other objects of the present invention will be understood upon a consideration of the following specification, claims and the single figure appended hereto.

The single figure is a schematic illustration of the control.

Referring now to the single figure, the numeral 10 represents a fuel burner which may be of any desired type and may be of the type having an electric igniter for the fuel. For indicating the need for operation of the fuel burner 10, a thermostatic switching device 11 may be provided which, when actuated, is effective to cause the controls located within the housing 12 to energize the burner 10. The burner 10 will remain operative until such time as the thermostatic switching device 11 no longer indicates a need for operation of the burner.

25 The thermostatic switching device 11 may be seen to consist of a bimetallic element 15 which is effective upon temperature changes to move a switch blade 16 into and out of engagement with an associated switch contact 17.

The main controls of the present invention are 30 located in the housing 12. These controls include a source of power which is indicated by the numeral 20 and which may be an electric transformer having a primary winding 21, which may be connected to any suitable source of power, 35 and a secondary winding 22 having a tap at 23. A main burner control relay for initiating operation of the burner is provided in a relay 24 and this relay consists of a relay winding 25 and switch blades 26 and 27 which are normal when 40 deenergized so that blade 26 engages a contact 28 and blade 27 is out of engagement with a contact 29.

The numeral 30 represents a flame detector which may be of the type disclosed in my copending application Serial No. 465,476, filed November 13, 1942, for "Control Device," now Patent No. 2,448,503, granted Aug. 31, 1948. Associated with this control device or flame detector is a photocell 31 which may be disposed in any desired 45 manner to view the flame emitting from the burner 10. The output relay for the flame detector 30 may be seen to consist of a relay winding 32 which is operative when energized to move a switch blade 33 from engagement with switch contact 34 into engagement with a switch contact

35. The switch contacts 34 and 35 are resiliently mounted contacts which are effective as overlapping contacts. These contacts cooperate with switch blade 33 so that when the switch blade is moved from the deenergized position, where it is contacting switch contact 34, through the intermediate position it will be engaging switch contact 34 as well as switch contact 35 so that there is always an electrical circuit completed through the switch blade 33 as it switches from the deenergized to the energized position or vice versa.

The numeral 40 indicates a safety cutout device for the subject control apparatus and may be seen to consist of a safety switch heater 41 which is effective, upon being energized for a predetermined length of time, to cause the bimetal 42 to be warped out from under the switch contacts 43 and 44 so that the same will separate and break an electrical circuit. For resetting the safety cutout device, a reset actuator 45 is provided. This actuator is so designed that depressing the actuator raises the contacts 43 and 44 from the return path of the bimetal 42 without allowing the contacts to close until the bimetal 42 is back in its normal position and the actuator is released. If the bimetal is not back in its original position it will be impossible for the switch contacts 43 and 44 to close.

Operation

Considering the operation of the subject invention it will first be noted that the apparatus, as shown in the drawing, is in the deenergized position with the thermostatic device 11 not indicating a need for operation of the burner 10 and the burner control relay 24 and flame detection relay 30 both in the deenergized position. In the event that the space wherein is located the thermostatic device 11 should cool, the temperature of the bimetal 15 will decrease and cause the switch blade 16 to be moved into engagement with switch contact 17. When this occurs an energizing circuit will be completed to the burner control relay 24 and this circuit may be traced from the upper terminal of the secondary winding 22 through conductor 50, switch contact 17, switch blade 16, bimetal 15, conductor 51, relay winding 25, conductor 52, switch contacts 43 and 44, conductors 53 and 54, switch blade 33, switch contact 34, conductors 54 and 55, heater 41, and conductor 56 back to the lower terminal of the secondary 22. With this energizing circuit completed the relay 24 will become energized and the switch blade 26 will move into engagement with its associated contact 29 to complete an energizing circuit to the burner 10. This energizing circuit may be traced from the input power line 58 through conductor 59, switch contact 29, switch blade 27, conductor 60, burner 10, and conductor 61 back to the other input power line 57. With this energizing circuit completed, the burner will be brought into operation and there should be a flame or combustion emitting from the burner 10 and, if so, this will be detected by the photocell 31 located in the output of the burner. When this flame is detected, the flame detection relay 30 will become energized and the relay winding 32 will move the switch blade 33 from engagement with switch contact 34 into engagement with switch contact 35. As mentioned above, this switching is accomplished without interruption of an electrical circuit through the switch blade 33 because of the fact that the contacts 34 and 35 are overlapping. The need for this will be understood when it is noted that the energization of the flame detection

relay connects the relay 24 in a relay maintaining circuit independent of the first traced circuit and independent of the safety cutout device 40. This relay maintaining circuit may be traced from the upper terminal of the secondary 22 through conductor 50, switch contact 17, switch blade 16, bimetal 15, conductor 51, winding 25, conductor 52, switch contacts 43 and 44, conductors 53 and 54, switch blade 33, switch contact 35, and conductor 62 back to the tap 23 on the secondary 22. It will be noted that this last traced circuit does not include the safety cutout heater 41 for the circuit to this safety cutout heater was opened by the movement of the switch blade 33 from the switch contact 34.

The burner is now in the operating position with both the burner control relay 24 and the flame detection relay 30 energized. The burner will remain in the operating position until such time as the thermostatic device 11 no longer indicates a need for operation of the burner 10. When the bimetal 15 of the thermostatic device 11 has become heated sufficiently, the switch blade 16 will be moved from its engagement with switch contact 17 and the energizing circuit for the relay 24 will be opened. With the relay 24 deenergized, the switch blade 27 will move out of engagement with switch contact 29 which in turn will cause the burner 10 to become deenergized. With burner 10 no longer operating there will be no flame detected by the photocell 31 and therefore the flame detection relay 30 will become deenergized and the switch blade 33 will move out of engagement with switch contact 35 and into engagement with switch contact 34 to put the control apparatus back in the condition it is shown upon the drawing. The apparatus is now in a condition for another operating cycle.

Operation upon flame failure

Assume for the moment that the burner 10 and the control apparatus 12 were operating properly and are in the energized position with relay 24 energized and flame detection relay 30 energized. 45 In the event there should now be a flame failure, the photocell 31 will no longer detect flame and the flame detection relay 30 will become deenergized. With relay 30 deenergized the switch blade 33 will move out of engagement with switch contact 35 and into engagement with switch contact 34. The movement of the switch blade 33 to this position will reconnect the safety cutout heater 41 into the energizing circuit of the relay 24 and this circuit may be traced from the upper terminal of the secondary 22 through conductor 50, switch contact 17, switch blade 16, bimetal 15, conductor 51, winding 25, conductor 52, switch contacts 43 and 44, conductors 53 and 54, switch blade 33, switch contacts 34, conductors 54 and 55, heater 41, and conductor 56 back to the lower terminal of the secondary 22. In the event that combustion is not re-established in the burner 10 the continued energization of the safety cutout heater 41 will result in the warping of the bimetal 42 out from under the switch contacts 43 and 44. With said bimetal out from under the switch contacts 43 and 44 these contacts will separate and will open the energizing circuit for the relay 24 and the cutout heater 41. With relay 24 deenergized the switch blade 27 will move out of engagement with switch contact 29 to open the energizing circuit for the burner 10 so that now both the control apparatus and the burner 10 will remain inoperative until such time as the reset actuator 45 is depressed to permit the closing of

the switch contacts 43 and 44. As mentioned above, these contacts cannot close until such time as the bimetal 42 has moved back to the normal position as it is shown upon the drawing.

Upon the closing of the switch contacts 43 and 44, caused by the movement of the bimetal back to its normal position and the subsequent depressing of the actuator, the energizing circuit to the relay 24 will again be completed. The apparatus will then initiate operation of the burner 10 and in the event that the re-energization of the burner does not establish combustion the safety cutout heater will again warp the bimetal 42 from under the contacts 43 and 44 and the energizing circuit for the relay 24 will again be broken.

Obviously, in the event that flame is not established on the initial energization of the relay 24 by the closing of the thermostatic device 11, the safety cutout heater 41 will be energized and will warp the bimetal in the manner mentioned above when flame was not established upon the depressing of the reset actuator 45.

Operation of false indication of flame

Assume the apparatus has been operating properly with both the burner control relay 24 and the flame detection relay 30 energized and now the thermostatic device indicates no further need for operation of the burner 10. This will mean that the switch blade 16 is moved out of engagement with switch contact 17. It will further mean that the relay 24 will become deenergized and the switch blade 27 moved out of engagement with contact 29 to cause deenergization of the burner 10. Assume now that there is some fault in the flame detection relay 30 which causes continued energization of the winding 32 so that the switch blade 33 remains in engagement with switch contact 35. This condition will obviously result in a false indication of flame when the burner 10 is no longer energized.

With these conditions present, an energizing circuit will be completed to the safety cutout heater 41 and this circuit may be traced from the tap 23 of secondary 22 through conductor 62, switch contact 35, switch blade 33, conductors 54 and 64, switch blade 26, switch contact 28, conductors 65 and 55, heater 41, and conductor 56 back to the lower terminal of the secondary 22. With this last traced circuit complete, the heater 41 will cause the bimetal to warp toward the right and allow separation of the contacts 43 and 44 so that they will open-circuit. As long as they are open-circuited it will be impossible to connect the burner control relay 24 in an energizing circuit and start operation of the burner.

It will further be noted that continued energization of the heater 41 will be had as long as the switch blade 33 engages switch contacts 35 and switch blade 26 engages contact 28 so that the subsequent depressing of the actuator or reset button 45 will not result in the closing of the contacts 43 and 44 as the bimetal will be in the warped position and it will be impossible for the contacts 43 and 44 to close upon the depressing and release of the actuator 45. This condition will exist until such time as the fault has been cleared from the flame detection relay 30 so that the switch blade 33 moves into engagement with switch contact 34 to complete an energizing circuit for the burner control relay 24 upon the subsequent closing of the contacts 43 and 44 and

the called for operation of the burner by the thermostatic device 11.

The apparatus then provides a component checking arrangement whereby it is impossible to energize the burner 10 when the flame detection relay 30 is falsely indicating proper operation of the burner while it is possible to energize the burner when there has been a flame failure as pointed out above. It will further be noted that the control apparatus employs only three switch contacts, independent of the burner control contacts, in accomplishing its shutdown upon flame failure and false indication of flame.

From the foregoing it will be seen that I have provided a burner control apparatus which requires a minimum of switch contacts while also providing an apparatus that will fail safe in the event of a flame failure or in the event there is a false indication of flame. While I have disclosed one particular embodiment of my invention it will be obvious to those skilled in the art that there are many ways in which the foregoing could be accomplished and therefore I intend to be limited solely by the scope of the appended claims.

I claim:

1. In a burner control apparatus, a source of power, a safety switch device having a pair of switch contacts and a heater therefor which heater is operative to cause opening of said safety switch contacts after a predetermined length of time to render the control apparatus inoperative, a first relay which is operative when energized to cause energization of the burner, a second relay operated by means indicative of proper operation of the burner, said second relay having a switch blade and in and out overlapping contacts whereby said blade is always in engagement with one of said contacts, a first energizing circuit means for connecting said first relay to said power source adapted to be completed by means indicative of the need for operation of the burner, said circuit means including said safety switch heater and the out contact and switch blade of said second relay, second circuit means maintaining said first relay in an energizing circuit independently of said safety switch heater upon proper operation of the burner, said second circuit means including said source of power and the in contact and switch blade of said second relay, and means including said first relay when deenergized and the in contact and switch blade of said second relay for connecting said safety switch heater in an energizing circuit when said second relay is falsely indicating proper operation of the burner.

2. In a burner control apparatus, a source of power, a safety switch device having a pair of switch contacts and a heater therefor which is operative to cause opening of said safety switch contacts upon continued energization for a predetermined length of time to effect deenergization of said control apparatus, a thermostatic switch adapted to be closed upon an indication for need of operation of the burner, a first relay having in and out switch contacts, said relay adapted to cause energization of the burner upon becoming energized, a second relay having overlapping in and out switch contacts, said second relay normally being rendered operative upon proper operation of the burner, a first electric circuit for energizing said first relay, said circuit including said thermostatic switch, said safety switch contacts, the out switch contact of said

overlapping switch contacts, said safety switch heater and said source of power, a second electric circuit for maintaining said first relay energized independently of said safety switch heater and adapted to be completed without interruption of the energization of said relay, said second circuit including said thermostatic switch, the in contact of said overlapping contacts, and said source of power, and a third electric circuit adapted to be completed through said safety switch heater upon said first relay becoming de-energized and said second relay remaining in energized position, said third circuit including the in contact of said overlapping contacts, an out contact of said first relay and said source of power.

3. In combination in a burner control apparatus, a first relay for energizing the burner adapted to be energized by means indicative of the need for operation of the burner, a second relay which is rendered operative upon proper burner operation, means including contacts of said second relay for connecting said first relay in an energizing circuit and connecting said first relay in a maintaining circuit in uninterrupted sequence independently of any switch contacts of said first relay upon proper operation of the burner, a safety cutout device having an actuator and a pair of switch contacts with said actuator connected in said energizing circuit adapted when energized a predetermined length of time to effect deenergization of said first relay by opening said pair of contacts, and means including contacts of said first relay when deenergized and contacts of said second relay when in energized position for energizing said cutout device actuator continuously to prevent energization of said first relay.

4. In combination in a burner control apparatus, an electric transformer secondary winding having a tap thereon, a first relay for energizing the burner and adapted to be connected in an energizing circuit to the ends of said transformer winding by means indicative of the need for burner operation, a safety cutout device having an actuator and switch contacts in said last named energizing circuit and adapted to render inoperative said relay when said actuator has been energized a predetermined length of time, a second relay having overlapping in and out switch contacts, said second relay being energized upon proper operation of said burner, means connecting said out contact of said second relay in the energizing circuit of said first relay, means including the in contacts of said second relay for connecting in uninterrupted sequence said first relay in a maintaining circuit independently of any contacts of said first relay to said tap and discontinuing any circuit connection through said cutout device actuator, and means including contacts of said first relay when deenergized and the in contacts of said second relay for connecting said cutout device actuator in a circuit between said tap and an end of said transformer to render said apparatus inoperative when said second relay is falsely indicating proper operation of the burner.

5. In a burner control apparatus, a source of power, a first relay having an energizing circuit adapted when completed to cause energization of the burner, a safety cutout device having an actuator and switch contacts for rendering inoperative said electric means after said actuator has electric current passing therethrough for a predetermined length of time, a second relay

rendered operative upon proper operation of the burner, said second relay comprising a switch blade and a pair of associated contacts which are overlapping as said switch blade is moved from the deenergized position to the energized position, means including said cutout device actuator and contacts and said second relay switch blade and deenergized position contact connected in the energizing circuit of said first relay, means adapted to complete the energizing circuit of said first relay to said source of power upon a need for burner operation, means including said second relay switch blade and energized position contact for connecting said first relay in a maintaining circuit independent of said cutout device actuator and any switch contacts of said first relay to said source of power, and means including contacts of said first relay when in a deenergized position and said second relay switch blade and energized position contact for connecting said cutout device actuator in an energizing circuit to said source of power when said second relay is in operative position when there is no need for burner operation.

6. In a burner control apparatus, comprising in combination, a source of power, electrically energized first switch means for completing an energizing circuit to the burner, electrically operated second switch means for indicating proper burner operation, said second switch means including switch contacts which are continuously in engagement when the means is moved from the energized to the deenergized position, a safety cutout device including switch contacts and a heater which when energized for a predetermined length of time will cause said switch contacts of said device to be operative to shut down said apparatus, means connecting said heater in a first energizing circuit to said source of power when it is desired to initiate burner operation, said means including only switch contacts of said second switch means and means for indicating a need for burner operation, means for maintaining said first switch means in an energizing circuit to said source independently of said heater, said last named means including said source of power and switch contacts of only said second switch means when in energized position, and means connecting said heater in a second energizing circuit only when said first switch means is in deenergized position and said second switch means is in energized position, said second energizing circuit being independent of said switch contacts of said cutout device so that said heater is continuously energized until said second switch means is in deenergized position.

7. In combination in a burner control apparatus, first switch means having an operator therefor for completing an energizing circuit to the burner and adapted to be energized by means indicative of the need for burner operation, second electrically operated switch means which are rendered operative upon proper burner operation, means including said second switch means for connecting the operator of said first switch means in an energizing circuit and connecting the operator of said first switch means in a maintaining circuit in uninterrupted sequence independently of any switch contacts of said first switch means upon proper operation of the burner, a safety cutout device having an electrical actuator and switch contacts therefor in said energizing circuit adapted when energized a predetermined length of time to effect deenergization of the operator of said first switch means,

and means including contacts of said first switch means when said operator is deenergized and said second switch means when in energized position for rendering said cutout device actuator effective to prevent energization of said first switch means.

8. In a burner control apparatus, a source of power, a safety switch device having a pair of switch contacts and a heater therefore which is operative to cause opening of said safety switch contacts upon continued energization thereof for a predetermined length of time to effect deenergization of said control apparatus, a control circuit adapted to be closed upon an indication for need of operation of the burner, a first relay having in and out switch contacts, said relay adapted to cause energization of the burner upon becoming energized, a second relay having overlapping in and out switch contacts, said second relay normally being rendered operative upon proper operation of the burner, a first electric circuit for energizing said first relay, said circuit including said control circuit, said safety switch contacts, the out switch contacts of said overlapping switch contacts, said safety switch heater

5 and said source of power, a second electric circuit for maintaining said first relay energized independently of said safety switch heater and adapted to be completed without interruption of the energization of said relay, said second circuit including said control circuit, the in contacts of said overlapping contacts and said source of power, and a third electric circuit adapted to be completed through said safety switch heater upon 10 said first relay becoming deenergized and said second relay remaining in energized position, said third circuit including the in contact of said overlapping contacts, out contacts of said first relay, and said source of power.
